UNITED STATES PATENT OFFICE

JOHN ELLIS OSTLINE, OF LIVERPOOL, ENGLAND, ASSIGNOR TO ASSOCIATED TELEPHONE AND TELEGRAPH COMPANY, OF KANSAS CITY, MISSOURI, A CORPORATION OF DELAWARE

TELEPHONE SYSTEM

Application filed August 28, 1928, Serial No. 302,613, and in Great Britain September 5, 1927.

The present invention relates to telephone systems and is more particularly concerned with arrangements for giving tones to calling parties to indicate the progress of a connection. Such tones are sometimes employed in manual systems, but in automatic systems they become almost essential in view of the fact that there is no operator to inform the calling party how the call is progressing. It has usually been considered desirable in automatic systems to give a calling party what is known as a ringing tone which may be described as an echo of the ringing of the wanted party's bell, from which the calling party gathers that the connection has been properly set up and that if he receives no reply it is because the wanted party has not answered. The simplest method of supplying this tone is to allow some of the actual ringing current to leak back through a small condenser in the direction of the calling party's station, and this arrangement is found quite satisfactory when ringing generators are employed of the pole-changer type which give a wave with very sharp peaks and hence a considerable proportion of higher harmonics. In case, however, a rotary alternator giving a close approximation to a sine wave is made use of, it is found that the amount of ringing current of suitable frequency which leaks back through the ringing tone condenser is not sufficient to give the calling party the required audible indication. One method of overcoming this difficulty which has been employed is to superimpose on the ringing current a tone obtained from an independent tone source; for instance the lead from the generator may pass through the secondary of a transformer, the primary of which is connected to a high-speed interrupter. In this case it is clear that the calling party will receive ringing tone in exact correspondence with the ringing of the wanted party's bell. It has been found however that the tone obtained by this means is subject to considerable variation in volume in accordance with the load on the generator and that when this load is very heavy the ringing tone obtained is almost inaudible and therefore unsatisfactory. The present invention aims at overcoming

this difficulty so that a tone of constant volume is obtained irrespective of the number of bells which are being supplied from the ringing generator at any particular instant.

According to the invention this is effected by arranging that the ringing current and ringing tone are obtained from separate sources so that they are entirely independent and do not interfere one with the other. In order to avoid modifying standard connector circuits and thus still permit both to be fed over a single lead it is then desirable that ringing tone shall be supplied in the intervals when actual ringing current is not being fed to the connector; since as already pointed out, the ringing current itself, when a pure sine wave, is inaudible to a calling party this will occasion no difficulty.

The invention will be appreciated from the following description of one method of carrying it into effect which should be taken in conjunction with the accompanying drawing. This arrangement is designed for a system in which ringing current is supplied intermittently for periods of equal length separated by alternate long and short pauses. This arrangement while possessing other advantages permits a ringing tone corresponding exactly thereto to be readily differentiated from other tones such as busy tone, which in addition to being of different pitch is applied in pulses which alternate with silent intervals of the same length. It will be apparent therefore that if the ring-back tone were applied for the whole time that ringing current was not being applied, the tone received by the calling party would not correspond exactly with the actual ringing conditions. In the arrangement shown, therefore, two interrupters are employed, for instance with the phase relationship shown, which are mounted on the same shaft and thus rotate together. The lead L is a common lead extending to a group of connector switches or cord circuits if ringing current is to be supplied to a manual operator's position. In the position of the cams C1, C2 shown, this lead L is connected to earth and neither tone nor ringing current is therefore being fed out. As the cams rotate in the

direction indicated by the arrow, cam C2 will operate its associated spring and tone from the transformer T will therefore be connected out to lead L. After this tone is removed, cam C1 will operate its associated springs and the generator G will then be connected out to supply ringing current while the transformer T will be entirely cut off. It will be readily apparent to those skilled in the art that with this arrangement the ringing tone will correspond exactly with the actual ringing current periods but that the two will never be applied together. In the arrangement shown the tone is obtained from the high speed interrupter I but clearly any other suitable tone generator may be employed. Furthermore it would also be possible to operate both sets of interrupter springs from a single cam, the springs then being located substantially 180° apart to produce the same effect as the arrangement shown.

I claim:—

1. In a telephone system, a source of ringing current and a source of ringing tone, two cam-controlled interrupter springs; a conductor connected to the first of said springs, a front contact for said first spring for connecting said conductor to said ringing-current source, a back contact for said first spring for extending said conductor to said second spring, a front contact for said second spring for connecting said conductor to said ringing-tone source, and a back contact for said second spring for grounding said conductor when disconnected from both of said sources.
2. In a telephone system, a conductor, a source of ringing current and a source of ringing tone, means for connecting said ringing-current source to said conductor at intervals to produce a ringing signal at the called station followed by a relatively long silent period, said ringing signal being inaudible to the calling subscriber, and means for connecting said ringing tone source to said conductor at like intervals during said silent periods to provide a ringback tone for the calling subscriber which simulates said ringing signal.
3. In a telephone system, a conductor, a generator for generating ringing current having substantially a sine curve wave form which will not leak back through a small condenser and is therefore inaudible to a calling subscriber, a source of ringing tone, a cam-controlled interrupter spring for connecting said generator to said conductor at intervals to produce a ringing signal followed by a relatively long silent period, and a second cam-controlled interrupter spring for connecting said ringing tone source to said conductor at like intervals during said silent periods to provide a ringback tone which simulates said ringing signal.
4. In a telephone system, a conductor, a

source of ringing current and a source of ringing tone, means for connecting said ringing current source to said conductor at definite periods in accordance with a predetermined code, there being a relatively long silent period between the end of one code signal and the beginning of the next code signal, and means for connecting said ringing tone source to said conductor in accordance with said code during said silent period to provide a code tone signal for the calling subscriber which simulates said code ringing signal.

In testimony whereof I have signed my name at Liverpool, England, this 14th day of August 1928.
